UNITED STATES PATENT OFFICE.

WILLIAM B. SMITH WHALEY, OF MALDEN, MASSACHUSETTS, ASSIGNOR TO AMERICAN WHALEY ENGINE COMPANY, OF BOSTON, MASSACHUSETTS, A CORPORATION OF MASSACHUSETTS.

IGNITION APPARATUS FOR INTERNAL-COMBUSTION ENGINES.

1,319,197.

Specification of Letters Patent.

Patented Oct. 21, 1919.

Application filed November 2, 1917. Serial No. 199,813.

To all whom it may concern:

Be it known that I, WILLIAM B. SMITH WHALEY, a citizen of the United States, and resident of Malden, in the county of Middlesex and State of Massachusetts, have invented a new and useful Ignition Apparatus for Internal-Combustion Engines, of which the following is a specification.

My invention relates to ignition apparatus for internal combustion engines and pertains more particularly to apparatus for controlling, actuating and timing the ignition generator devices rendering more flexible the operation of the engine. Said apparatus is adapted to all types of internal combustion engines to operate ignition devices or any intermediate devices associated therewith, controlling, reversing or otherwise timing the same to readily respond to all operating conditions of reversing or non-reversing engines and for varying the speeds or control thereof in any direction of rotation of said engines.

The invention is especially applicable to internal combustion engines employing a flexible cycle of operation similar to that of the so-called retarded combustion cycle, and is flexible in its control and timing of ignition to meet the conditions of flexibility of the engines. All changes of operation of the engine due to varying load or operating conditions may be met with in each change of operation of the cycle by the said flexible control and operation of this ignition apparatus.

In order to illustrate my invention I have shown in the accompanying drawings one embodiment thereof as applied to an internal combustion engine employing a flexible cycle of operation such as, or similar to, the internal combustion engine disclosed in my co-pending application Serial No. 138,207, filed December 21, 1916.

In the drawings:

Figure 1 is a partial end elevation of an internal combustion engine and associated parts such as disclosed in said co-pending application with my present invention applied thereto and operated by the so-called Stephenson valve-link mechanism illustrated in the dead center position and with the timing elements in the position of maximum late or lag for late timing or late ignition.

Fig. 2 is a similar end elevation of a por-

tion of Fig. 1, with the ignition and timing elements in the maximum late timing or ignition position after ignition has taken place.

Fig. 3 is a view similar to Fig. 2, with the ignition elements in the extreme starting position before ignition and with the operating links shifted to operate as when running ahead.

Fig. 4 is a horizontal section on line 4—4 on Fig. 3.

Fig. 5 is a horizontal section on line 5—5 on Fig. 4.

Fig. 6 is a partial left hand end view of the engine shown in Fig. 1.

Fig. 7 is a right hand end elevation similar to that of Fig. 6.

Fig. 8 is a sectional plan on line 8—8 on Fig. 6, looking in the direction of the arrows.

Fig. 9 is a transverse section on line 9—9 on Fig. 8.

Figs. 10, 11 and 12 are detail diagrams showing the performance of the timing elements at different positions or steps for one setting for early ignition.

Figs. 13, 14 and 15 are detail diagrams showing the performance of the timing elements at different positions or steps for maximum early ignition.

Fig. 16 is a vertical transverse section on line 16—16 on Fig. 1, showing the latch mechanism of a reciprocating type of high tension impulse generator in position to move the armature thereof to the firing or ignition position.

Fig. 17 is a similar view to Fig. 16, but with the latch of the ignition generator tripped and the armature returned to the normal position after ignition.

Fig. 18 is a transverse vertical section on line 18—18 on Fig. 7.

Figs. 19 and 20 are diagrammatic views of one type of an oscillating high tension impulse generator.

Fig. 21 is a diagrammatic view of the tripper arm on the ignition generator in Figs. 19 and 20.

The terms employed herein are used in the generic and descriptive sense and are not primarily intended as terms of limitation of the invention.

In illustrating my invention and the adaptability thereof to an internal com-

tion engine employing a flexible cycle of operation, I have disclosed the same as applied to a retarded combustion cycle internal combustion engine of the two-cycle type. The 5 construction and operation of an engine of this type is disclosed in detail in said co-pending application, Serial No. 138,207, filed December 21, 1916, which is referred to for the more complete description thereof. It 10 being sufficient herein to refer to the same generally except as it may be necessary to describe in detail such parts or functions as may lend themselves to any application, co-operation or coördination with this present 15 invention.

The invention herein is not limited in its application to engines of the type above referred to as the same may be applied to many other forms or types of internal combustion engines of the different known cycles. 20

Therefore, in this specific application, the numeral 30 in its entirety represents the cylinder of a vertical internal combustion engine mounted upon the crank case 31 of any 25 preferred construction. The engine is provided with the usual crank-shaft, piston, connecting rod and the like, and on said shaft is secured in any suitable manner the ordinary and conventional form of double 30 eccentrics usually employed with the so-called Stephenson valve-link mechanism of the type to be found in the ordinary steam engine employing a slide valve to control the admission of steam to the cylinder therefor. I may employ any other form of links, 35 link motion or mechanism than that herein for the purposes hereinafter set forth, and I am not limited to any particular form or type of the same provided said purposes are 40 carried out.

Therefore, I have illustrated in the drawings but a portion of said Stephenson links comprising the segment 35, the eccentric rods 36 and 37, and the usual link-block 38 45 slidable in said segment.

An adjusting link 39 is pivoted to said segment and to the lever 40 to be operated by the adjusting hand wheel 41 to position the said segment for the different degrees of 50 throw or movement to be imparted by the link motion to associated parts and for reversing said throw or movement.

Coöperating with the said link block 38 is a link 42 serving to maintain the said block 55 and the movement thereof in a definite manner for substantially vertical movement. Also pivoted to said block and to one arm of the rocker 43 pivoted on the crank case 31 is a link 44. To the other arm of the said 60 rocker is pivoted the actuating link 45 extending to, and pivoted to the operating arm 46 of the bell-crank or rocking member 47 on the fixed stud 48 supported by the bracket 49 bolted or otherwise secured from 65 a convenient point herein, on the cylinder

30. The rocking member 47 is provided with an elongated sleeve 50 and at the opposite end thereof in alignment with the arm 46 is another valve actuating arm 51 to which is pivoted the intermediate valve-link 70 52 swiveled on the lower end of the valve-stem 53.

At the top portion of the cylinder 30 is located the housing 54 within which is the reciprocating inlet controlling valve 55 for 75 fuel or for a fuel element (see Figs. 1, 4 and 5) secured to the end of the valve stem 53. In this embodiment the said valve is preferably of the hollow piston or sleeve type and adapted to be reciprocated by any reciprocating links, as an eccentric, or by a cam or the like as may be desired or may be preferred. Said valve herein is designed to regulate the flow of compressed air to the cylinder 30 to support and complete the combustion process and for stratifying the gases in the said cylinder thereafter. In other types of engines the puppet, or other type of valve employed, may be operated as described herein or otherwise, to coördinate 85 or to coöperate with the elements of this invention, as will be described.

As stated in said co-pending application there is provided a compressed air tank 56, or other medium of air supply, in communication with the said valve housing 54 and the valve 55 by means of the supply pipe 57 through which the flow of air is controlled by the shut-off valve 58, thereby to supply air—a constituent element of the 100 combustible mixture—to the combustion chamber within the cylinder 30.

A precompression chamber for the carboniferous gas elements of mixture is located in the lower portion 59 of the cylinder 105 which is provided with the carboniferous supply conduit 60 leading thereto and from said chamber the precompressed mixture is transferred to the combustion chamber through a transfer or inlet port (not shown) 110 in the well-known manner as in other types of two-cycle internal combustion engines. Also there are provided an exhaust conduit or manifold 61 and an exhaust port (not shown) leading from the lower portion of 115 the combustion chamber at the lowest point of the stroke of the piston.

In the embodiment herein of the ignition apparatus the same is illustrated as associated for convenience or otherwise with the valve and valve actuating mechanism above described. If desired and convenient, the said ignition apparatus may be actuated by an independent link mechanism or operating mechanism.

Having thus described the apparatus for actuating the valve 55 and associated parts, I will now set forth the manner in which the ignition apparatus may be operated from the same mechanism or the equivalent thereof. 125 130

Another crank arm 66 on the said rocking member 47 is pivoted at 67 to the link 68 fulcrumed at 69 to the free end of the tripper latch 70 which operates an impulse 5 generator hereinafter described. The latter is in turn pivoted at 71 to the divided journaled timing member 72 bearing on the said elongated sleeve 50. Also, a crank arm 75 on the said rocking member 47 is pivoted at 10 76 to a cam link 77, the latter having the opposite end thereof pivoted at 78 to the connecting link 79 in turn pivoted at 80 to the said timing member 72. Said cam link 77 has thereon a cam portion 82 to engage with the operating means of a second impulse ignition generator hereinafter described.

The said timing member is normally stationary and is provided with an adjusting 20 arm 85 to which is pivoted at 86 the link 87 connected to or pivoted at 88 to the adjusting means herein shown as a bell-crank 90 swiveled at 91 on some portion of the cylinder 30. The other arm 92 of said bell-crank has pivoted thereto at 93 a link 94. Said link 94 is also pivoted at 95 to the adjusting handle 96 pivoted at 97 on the said cylinder 30. The adjusting handle is provided with the pivoted latch 98 co-operating 30 with the notches of the stationary quadrant or segment 99.

Several types of high tension impulse ignition generators are well known in the art, and for convenience I have illustrated two 35 thereof of a character adapted for ignition purposes for internal combustion engines of the type disclosed herein and for other types of engines. Large internal combustion engines are preferably provided with a plurality of ignition generators or apparatus 40 of which the following combine desirable features.

100 represents the permanent magnets of the so-called "Bosch" magneto type of high 45 tension impulse generator having a rotor 101 partially rotatable in the magnetic field between the poles of the said magnets. A suitable shaft 102 therefor is provided, and secured to one end of the same is a tripper 50 arm 103 normally projecting with the path of movement of the tripper latch 70. A pair of oppositely or diametrically disposed centralizing springs 105 secured to the stationary posts 106 extending from a bracket 55 107 are also secured to the extensions 109 on the hub of the tripper arm 103.

The rotor 101 is provided with the usual 60 commutator and a pair of brushes or collectors (not shown), one of which is connected or grounded to the frame of the engine and the other is connected to the lead wire 112 in circuit with the usual spark plug 113 thus to complete the circuit to the spark-gap.

65 The other ignition generator illustrated,

comprises also a permanent magnetic field and high tension coils or windings, as in the type just described, but contained within the housing 115. In this type the windings may be stationary and the magnetic field 70 movable, being connected to a slideable latch block 118 within the path of movement of the tripper or latch 119 on the slideable member 120 having a roll 121 on the end thereof co-operating with the cam 80. 75

A stationary throw-off or releasing portion 125 is adapted to engage with the latch 119 at a point near the end of the stroke of the member 120 to disengage the said latch from the latch block to allow the aforesaid magnet to be snapped back to normal position by a return spring (not shown) creating an impulse in the said winding by the movement of the said magnetic field.

An adjusting cam 126 pivoted at 127 on 85 the housing 115 is adapted to change the relative position of the said throw-off to disengage the said latch earlier or later as may be desired. A spring (not shown) normally maintains the roll 121 of the member 90 120 in engagement or in contact with the cam 80 when moved thereagainst.

The said windings are provided with a pair of terminals, one of which is grounded to the frame or engine, and the other is 95 connected to the lead wire 129 in circuit with the usual spark plug 130 to complete the electric circuit to the spark gap.

This igniter is of the so-called "Wico" type adapted in its operation to magnetize 100 and suddenly demagnetize one or more magnetic coils positioned within the permanent magnetic field and is operated by a relative reciprocating action between the said field and said coils.

105 The operation of my invention is as follows:

The hand wheel 41 is operated to move the adjusting link 39 to position the segment 35 in the desired position for early 110 or late cut-off of the valve 55 for either "ahead" or "reverse" operation of the engine.

In Fig. 1 the said segment 35 is shown in the mid or neutral position, and as is well 115 known no movement of the valve 55 is had although the eccentrics and links 36 and 37 perform their usual movements. Therefore, the parts or elements connected with the actuating link 45 are in the mid or neutral position and no movements of any of said parts will take place and the engine will not operate.

Also in said figure the adjusting handle 96 has been moved in an extreme down position, as shown in full lines, throwing the bell-crank-arms 90 and 92 in the corresponding position to move the link 87 upward throwing the arm 85 upward rotating the timing member 72 on the sleeve 50 to the 130

left to position the tripping end of the tripper latch 70 to the right so as to provide for maximum late ignition.

This position of the parts just described is maintained the same in Figs. 2 and 3. The segment 35 in the latter figures has been moved by the adjusting handle 41 and the adjusting link 39 to the right on the block 38 for "forward" running of the engine. In Fig. 3 the actuating-link 45 is illustrated in the uppermost position to commence the down stroke. In Fig. 2 the said actuating-link 45 has moved down to the extreme end of the stroke thereof, moving the valve 55 down to open the admission ports co-operating therewith and moving the crank arm 66 with it to cause the tripping arm 103 to move from the position in Fig. 3 to the dotted position in Fig. 2 where the said arm has just been released from said tripper latch 70 and has "snapped" back to the full line position under the action of the equalizing springs 105.

The said segment 35 may also be moved to the left relative to the said block 38 for "reverse" running of the engine and reciprocations will be imparted to the actuating-link 45 in the same manner, commencing first with an opposite reciprocation to that for "forward" running of the engine. The effect of the said change of the segment is to reverse the position of the valve 55 and the position or stroke of the crank arm 46 and all parts associated therewith. It will be understood that when the crank arm 46 has reversed its position that the tripper latch 70 and the cam 82 are also reversed, but thereafter the reciprocations of the actuating-link 45 will be the same except at the starting position thereof.

Referring now to Figs. 1, 2 and 3, the adjusting handle 96 when in the full line position, places the bell crank arms 90 and 92 in the corresponding position, and by means of the link 87 and arm 85 the member 72 is positioned for maximum late ignition, as illustrated. In this position the lower end tripper latch 70 is moved to the left, and by reason of the link 68 the free end of said latch is moved in the opposite direction to delay contact thereof with the arm 103 irrespective of the then position of the crank arm 66. Likewise, the link 79 pulls the cam link 77 slightly upward about the pivot 76 to delay engagement of the cam 80 with the end of the slidable member 120.

Referring to Fig. 21 the point of release of the arm 103 is substantially on the line "A—A" for maximum late ignition which line corresponds to the said full line position in Fig. 1 of the timing parts just referred to.

In the mid dotted line position "B" in Fig. 1, the bell crank arms 90 and 92 have moved the link 87 and arm 85 down, rotat-

ing the member 72 to the mid-position, illustrated in Figs. 10 to 12 inclusive for early ignition, as illustrated by the line of release or ignition "B—B" on the said diagram Fig. 21.

70

In Figs. 10 to 12 inclusive, the relative positions of all parts are illustrated throughout the successive steps of the operation of the ignition apparatus for the said mid-position or early ignition, as will be described hereinafter.

In the dotted line position "C" in Fig. 1, the said adjusting handle 96, the bell crank arms 90 and 92, the link 87 and the arm 85 are positioned for maximum early ignition as illustrated also in Figs. 13 to 15 inclusive and along the line of ignition "C—C" on Fig. 21. This operation places the member 72 in the position shown to move the pivots 71 and 80 in the clockwise direction to move the lower end of the tripper latch 70 and the upper end of the link 79. The upper end of the tripper latch is thereby moved to the left or nearer the tripper arm 103 to engage the same earlier than before, while the cam lever 77 is now moved downward to cause the cam 82 to engage the slidable member at an earlier point.

The above description refers to the manner of adjusting or varying the timing apparatus intermediate of the means for actuating the same. It will be remembered, however, that the link mechanism may be adjusted or varied to increase or decrease the throw of the rocking member 47 and therefore increase or decrease the range of throw of both the tripper latch 70 and the cam 82 by reason of the greater or lesser movement of the rocking member 47.

The successive steps of the operation of the last described mechanisms may best be understood by reference to the Figs. 10 to 21 inclusive, which illustrate the different positions of said mechanisms for three settings of the timing elements, to wit, maximum late ignition, early or mid ignition and maximum early ignition, respectively.

In Fig. 3, the segment 35, arm 46 and actuating-link 45 are shown in the extreme upward position or at the beginning of the downward movement. Therefore, the tripper latch 70 is at this time entirely out of engagement with the tripper arm 103 and the slidable member 120 is in extreme "up" position, and both said latch and cam are positioned to begin their ignition operations.

The member 72 being normally stationary any downward movement of the bell-crank-arm 46 will first cause corresponding movement of the bell-crank-arms 66 and 75. This movement will be communicated to the link 68 and the upper end of the tripper latch 70 moving the same into position against the tripper arm 103. At the same time the cam link 77 will be moved horizon- 125

130

tally with a substantially parallel motion on the pivot 76 and the link 79 bringing the cam 82 from the position in Fig. 3 into further engagement with the slidable member 120. This second step is illustrated in the maximum late ignition position in Fig. 1, the early ignition position in Fig. 10, and the maximum early ignition position in Fig. 13. Further movement of the parts just described are illustrated by the next or third step as in Fig. 11 for the point of early ignition and in Fig. 14 for the point of maximum early ignition in full lines and then followed by the maximum point of movement in dotted lines in both of said figures respectively. When this occurs the tripper arm 103 has been moved from the normal position illustrated in Figs. 2, 10, 13 and 19 to the position in Figs. 11, 14 and 20 oscillating the rotor 101 in the magnetic field between the magnets 100. At the point illustrated by the last three figures the tripper latch 70 slips off the end of the tripped arm 103 and the springs 105 will suddenly and quickly return the said arm and the rotor to the normal position inducing in the windings of the rotor a high tension impulse electric current which is caused to arc across the electrodes of the spark plug 113 in the well-known manner to ignite the charge within the cylinder 30.

During these steps the cam 82 has engaged and moved the slidable member 120 from the position in Figs. 10, 13 and 16 to the position in Figs. 11, 14 and 17 where the end of the latch 119 engages with the throw-off 125 allowing springs (not shown) to suddenly return the permanent magnet to the normal position between the associated coils to induce in the latter a similar high tension impulse electric current which is caused to arc across the electrodes of the spark plug 130 to also ignite the charge within the cylinder 30.

From the dotted line position in Figs. 11 and 14, the tripper latch 70 and the cam 82 are now moved in the opposite or return direction, rotating backwardly to a slight degree the tripper arm 103; also allowing the slidable member 120 to move upward until said latch and said cam and all coöperating parts will again be in the normal position, as illustrated in Figs. 3, 12 and 15 for the beginning of the next ignition operations. These return movements will not excite the generators to cause a spark at the spark plugs.

Thus it will be seen that early and late ignition may be had with my invention in its application to reversible internal combustion engines and the employment of high tension ignition generators, it being here noted that low tension ignition generators may be employed if so desired. Likewise the relative amount of movement of the

tripper latch and the cam may be regulated in conjunction with the movement and control of the admission valve movements and for reverse operation as well as for forward running of the engine.

Engineering practice and the successful operation of internal combustion engines of large horse-power rating require a plurality of ignition generators to successfully ignite the charge in the cylinders. Reliability of operation is another factor in the requirement of more than a single ignition generator and the preferred types of the latter are embodied in the so-called high tension impulse generators. Therefore, in conjunction with internal combustion engines of all types my invention in its application is designed to bring about substantially the same flexibility of operation as that obtained in steam engines.

By manipulating the adjusting cam 126 to change the position of the throw-off or releasing portion 125 relative to the latch 119, the "Wico" ignition generator may be adjusted if desired to create the magnetic impulse at any desired time within the range of the device. Therefore, this latter generator may be adjusted to cause ignition earlier or later than the "Bosch" ignition generator to produce a second delayed or advance spark independently of that produced by said "Bosch." This result is of great advantage in large units of internal combustion engines, producing better and assured ignition, or inducing ignition at relatively widely separated portions of the larger volume of gas.

I have described herein one embodiment of my invention, but it is to be understood that the latter is not essentially limited to the specific construction and organization of said embodiment, since the same may be varied without departing from the proper scope of the claims.

Having thus described my invention in detail, what I claim as new is:—

1. In an ignition apparatus for internal combustion engines, a plurality of varied types of ignition devices, a single and common means for varying the operation thereof and mechanism coöperating with the engine for actuating said means.

2. In an ignition apparatus for internal combustion engines, a plurality of varied types of impulse electric current generators in circuit with sparking members in the combustion chamber of an internal combustion engine and means coöperating with the engine for varying the time of operation of said generators and for actuating the same.

3. In an ignition apparatus for internal combustion engines, a variable valve actuating mechanism coöperating with the engine shaft, a plurality of varied types of high tension impulse electric generators in cir-

- 6
- cuit with the spark plugs in the combustion chamber of said engine, and mechanism interposed between said actuating mechanism and said generators for operating the latter.
5. 4. In an ignition apparatus for internal combustion engines, a plurality of high tension impulse electric generators in circuit with the spark plug in the combustion chamber of the engine, and an inlet valve operated by variable timing-means, actuating mechanism interposed between the said timing means and the said actuating mechanism for operating the latter and means for varying the time of operation of the said 10 actuating mechanism relative to the said variable timing means for the said valve.
5. In an ignition apparatus for internal combustion engines, an ignition device in circuit with the spark plug in the combustion chamber of the engine and reversing means coöperating with the engine shaft in combination with variable timing mechanism for actuating said ignition device.
- 20 6. In an ignition apparatus for internal combustion engines, a plurality of ignition devices in circuit with the spark plug in the combustion chamber of the engine and reversible means coöperating with the engine shaft in combination with variable timing 30 mechanism for actuating said ignition devices.
7. In an ignition apparatus for internal combustion engines, a plurality of ignition devices, means for varying the time of operation thereof and mechanism coöperating with the engine shaft for actuating said means and for reversing the time of operation thereof.
- 40 8. In an ignition apparatus for internal combustion engines, a plurality of ignition devices, a single means for simultaneously varying the time of operation of all of said devices, mechanism coöperating with the shaft of the engine for actuating said means and for reversing the time of operation thereof.
9. In an ignition apparatus for internal combustion engines, a plurality of varied types of ignition devices, a single means for simultaneously varying the time of operation thereof, and mechanism coöperating with the engine shaft for actuating said means and for reversing the time of operation thereof.
- 50 55 10. In an ignition apparatus for internal combustion engines, a high tension impulse ignition generator and mechanism coöperating with the engine shaft for varying the time of operation of said generator and for reversing the time of operation thereof.
- 60 11. In an ignition apparatus for internal combustion engines, a variable and reversible admission valve actuating mechanism coöperating with the engine shaft, a high tension impulse electric generator in circuit with
- the spark plug in the combustion chamber of the engine and mechanism interposed between said actuating mechanism and said generator for operating the latter.
12. In an ignition apparatus for internal combustion engines, a plurality of ignition generators, a variable and reversible timing means for operating an admission valve and actuating mechanism interposed between said means and said generators for operating the latter.
- 70 13. In an ignition apparatus for internal combustion engines, a plurality of ignition generators, variable and reversible timing means for operating an admission valve and variable actuating mechanism interposed between said means and said generators for operating the latter.
- 75 14. In an ignition apparatus for internal combustion engines, a plurality of high tension impulse electric generators in circuit with the combustion chamber of the engine, variable timing and reversing means operating an admission valve actuating mechanism interposed between the said means and said generators for operating the latter and means for varying the time of operation of said actuating mechanism relative to said generators.
- 80 15. In an ignition apparatus for internal combustion engines, an ignition device, actuating means for the same, variable timing mechanism interposed between the ignition device and the actuating means, and reversible mechanism coöperating with the engine shaft and the said actuating means.
- 90 16. In an ignition apparatus for internal combustion engines, an ignition device, pivotally actuating means for the same, and reversible mechanism coöperating with the engine shaft and the said actuating means for operating the latter.
- 95 17. In an ignition apparatus for internal combustion engines, a plurality of ignition devices, pivotal actuating means for the same, and reversible mechanism coöperating with the engine shaft and the said actuating means for operating the latter.
- 100 18. In an ignition apparatus for internal combustion engines, an ignition device, actuating means for the same, variable timing mechanism interposed between the ignition device and the actuating means, and reversible and regulatable mechanism coöperating with the engine shaft and the said actuating means.
- 105 110 19. In an ignition apparatus for internal combustion engines, an ignition device, a regulatable mechanism for actuating the same and means coöperating with the engine shaft and the said mechanism for varying and for reversing the operation of the latter.
- 120 125 20. In an ignition apparatus for internal combustion engines, a plurality of ignition devices, actuating means for the same, vari-
- 130

able timing mechanism interposed between the ignition devices and the actuating means, and regulatable and reversible mechanism coöperating with the engine shaft and 5 the said actuating means.

21. In an ignition apparatus for internal combustion engines, a plurality of ignition devices, a variable mechanism for actuating the same and means coöperating with the 10 engine shaft and the said mechanism for reversing and for varying the operation of the latter.

22. In an ignition apparatus for internal combustion engines, a plurality of ignition devices, pivotally movable actuating means 15 for the same, and reversible and variable mechanism coöperating with the engine shaft and the said actuating means for operating the latter.

23. In an ignition apparatus for internal combustion engines, a plurality of ignition devices, an actuating member therefor, variable means on the latter for simultaneously timing the operation of each of the former, 25 and reversible mechanism coöperating with the engine shaft and the actuating means for operating the latter.

24. In an ignition apparatus for internal combustion engines, a plurality of ignition 30 devices, a movable member, a variable member normally stationary, means for adjusting the variable member, and means interposed between the said movable member and the said variable member to operate the 35 said ignition devices.

25. In an ignition apparatus for internal combustion engines, a plurality of ignition devices, a movable member, a variable member normally stationary, means for adjusting 40 the position of the latter, means interposed between the said movable member and the variable member to operate the ignition devices and variable means coöperating with the engine shaft and the said movable member for operating the latter.

26. In an ignition apparatus for internal combustion engines, a plurality of ignition devices, a movable member, a variable member normally stationary, means for adjusting 50 the position of the latter, means interposed between the said movable member and the variable member to operate the ignition devices, and variable and reversible means coöperating with the engine shaft and the 55 said movable member for operating the latter.

27. In an ignition apparatus for internal combustion engines, a plurality of high tension impulse ignition generators, a movable 60 member, a variable member normally stationary, means for adjusting the position of the latter, means interposed between the said

movable member and the variable member to operate the ignition devices, and variable and reversible means coöperating with the 65 engine shaft and the said movable member for operating the latter.

28. In an ignition apparatus for internal combustion engines, a plurality of high tension impulse generators, a rocking member, 70 a variable member normally stationary, means for adjusting the position of the latter, means interposed between the said rocking member and the said variable member for operating the said generators, and 75 variable and reversible link mechanism coöperating with the engine shaft and the said rocking member to operate the latter.

29. In an ignition apparatus for internal combustion engines, a high tension impulse 80 ignition generator, a rocking member, a variable member normally stationary, means for adjusting the position of the latter, means pivoted to the said rocking member and the variable member to operate the said 85 generator, and variable and reversible link mechanism coöperating with the engine shaft and the said rocking member for operating the latter.

30. In an ignition apparatus for internal 90 combustion engines, an ignition device comprising a magnetic field and a current generating part, a movable member, variable mechanism thereon coöperating with the ignition device to cause movement between 95 said field and the generating part, and variable mechanism coöperating with the engine shaft and the said movable member to operate the same.

31. In an ignition apparatus for internal 100 combustion engines, an ignition device comprising a magnetic field and a current generating part, a movable member, variable mechanism thereon coöperating with the ignition device to cause relative movement 105 between said field and said generating part, and variable and reversing mechanism coöperating with the engine shaft and the said movable member to operate the same.

32. In an ignition apparatus for internal 110 combustion engines, a plurality of ignition devices each comprising a magnetic field and a current generating part, a movable member, variable mechanism thereon coöperating with the ignition devices simultaneously to cause relative movement between 115 said field and said generating parts, and variable and reversing mechanism to operate said movable member.

WILLIAM B. SMITH WHALEY.
